UNITED STATES PATENT OFFICE.

THOMAS WEARDEN, OF MANCHESTER, ENGLAND, ASSIGNOR OF ONE-HALF
TO EDWARD PENNINGTON, OF SAME PLACE.

PIERCING AND EYELETING MACHINE.

SPECIFICATION forming part of Letters Patent No. 629,000, dated July 18, 1899.

Application filed November 17, 1898. Serial No. 696,706. (No model.)

To all whom it may concern:

Be it known that I, THOMAS WEARDEN, a citizen of England, residing at Manchester, in the county of Lancaster, England, have invented certain new and useful Improvements in Piercing and Eyeleting Machines, of which the following is a full, clear, and exact description.

This invention relates to a machine for piercing cloth and other similar and suitable material and for fixing eyelets in the holes formed by the piercers. The piercing and eyeleting is performed in one motion of the machine, and one or any convenient number of holes may be simultaneously formed and eyeleted.

The accompanying drawings, to which I will hereinafter refer, illustrate the construction of the improved machine.

Figure 1 represents the complete machine in front elevation. Fig. 2 shows it in side elevation. Fig. 3 is a back elevation of part of the machine. Fig. 4 illustrates a part of the brush which is employed in the eyelet box to keep the eyelets agitated and to feed them into the chute or chutes. Fig. 5 is an enlarged view of a piercer and its accessories soon after it has commenced its stroke. Fig. 6 is a similar view of the same parts in different relative positions. Fig. 7 is a further illustration of the same parts when the piercer is at the end of its stroke and the eyelet is being riveted in place. Fig. 8 shows a modification.

It will of course be understood that although the machine illustrated is represented with a multiplicity of piercers these improvements are equally applicable to a machine in which only one or any other convenient number of piercers are employed.

In its simplest form, then, the machine consists of a piercer which moves upward and pierces the cloth or similar material, then engages itself with an eyelet, passes farther upward, carrying with it the transfixed cloth and the eyelet, and finally enters a fixed upper die or anvil, by means of which the eyelet is pushed into the cloth and is riveted in place. When the piercer has entered the eye-

let, the chute in which the eyelet is contained is withdrawn laterally, so as to permit the further movement of the piercer. After the riveting has taken place the piercer is withdrawn and the eyelet-chute is returned, so as to interpose another eyelet in the path of the piercer ready for the next stroke.

Referring to the drawings, A is a frame, within which the slide B is capable of reciprocating vertically. It may be operated in any desired manner, but preferably by the eccentrics C, secured to the main shaft D, or by means of cranks and connecting rods. This slide is provided with a series of upwardly-projecting piercers E, each of which is formed with a thickened part or shoulder e, the function of which will be explained hereinafter. Above the piercers a series of eyelet-chutes F is arranged, each chute opening into a box G, which is mounted upon a shaft H so as to be capable of angular motion. At the top of the machine is a fixed series of dies or anvils I, these dies corresponding in number with the piercers.

The material to be pierced and eyeleted is placed upon the table J with the part to be pierced between the piercers and the overhanging chute ends. The eyelets in the ends of the chutes are thus visible to the operator. The machine is then set in motion. The piercers pass upward and pierce the cloth or other material K, which is supported against the chutes F, the piercers passing through holes or openings formed in the chutes or between adjacent chutes or between projections or horns formed on the chutes. In any case the chutes are so formed that each of them presents an eyelet L to the point of a piercer, the eyelets being held with their flanged parts uppermost. The piercers after perforating the cloth enter the eyelets, as shown in Fig. 5. The ends of the chutes are now withdrawn and the piercers are free to continue their upward motion, carrying with them the cloth K and the eyelets. Fig. 6 illustrates a piercer when this stage has been reached. The point of the piercer now enters an axial hole formed in its opposing die or anvil I, and the further movement of the piercer forces the eyelet into

the cloth and clenches it, the clenching being performed between the face of the die I and the shoulder e of the piercer E. This is shown in Fig. 7. The piercers are now withdrawn and are freed from the cloth, the latter being held or drawn off by the table J. The eyelet-chutes are now returned.

The chutes are preferably operated and withdrawn by the link N, Figs. 2 and 3. The lower end of the link is pivoted to the slide B, and its upper end engages by a slot n with a pin, stud, or shaft O, which is connected with the chutes, they in turn being connected to the eyelet-box G, which, as before explained, is capable of angular movement around the shaft H.

With the various parts in the positions shown in Fig. 2 it will be seen that the first part of the upward movement of the slide B communicates no motion to the chutes. As soon, however, as the piercers have engaged with their eyelets the bottom of the slot n has come into contact with the stud O, so that continued motion of the link withdraws the ends of the chute in the direction of the arrow. Upon the return motion of the slide the chutes are not returned until the upper end of the slot reaches the stud O and draws them back to their former position. This does not take place until the piercers are low enough to permit of the motion.

In order to insure that the chutes remain in their withdrawn position until it is time for them to return, a frictional device or brake may be employed. This may consist of an arm Q, one end of which is loosely connected to the stud O, while the other end is capable of passing under the spring-controlled clamp q. The friction between the clamp and the arm holds the chutes in their withdrawn position until the link N becomes operative.

An improved device for insuring the constant agitation of the eyelets in the box G whether the machine is working or not is represented in Figs. 1, 2, 3, and 4. This device also permits of the agitation being performed by hand. Mounted lengthwise within the box and capable of reciprocating or sliding therein is a rod or shaft R. This rod carries wire or other brushes r. (See Fig. 4.) Pivoted upon the side of the box is a crank-lever S, provided with a handle s and pulled constantly in one direction by the spring S'. The lever is connected to the sliding rod R by the connecting-rod R'. Upon the end of the box and in a plane at right angles to the plane of the lever S is mounted a second crank-lever T, one of the limbs of which comes below one of the limbs of the lever S, as clearly shown in Figs. 2 and 3. The other limb of the lever T is connected by a rod t to a short crank or eccentric upon the constantly-running first-motion shaft U. As long as this shaft is running, therefore, the levers S and T have angular motion imparted to them, and the rod

R and the brushes r are reciprocated. Should it be desired to agitate the eyelets when the shaft U is at rest, it can easily be effected by moving the lever S by the handle s.

The chutes may be of the usual construction and arrangement, with the exception that their ends are formed to support the cloth during piercing; but it is preferred to form them with their channels approximately resembling a letter V in section instead of making the channels conform to the shape of the eyelet, as is usual. By the improved section shown in Fig. 5 the sides of the channel in the chute are straight and have no recesses which may become choked up. The risk of the eyelets becoming jammed is thus much reduced and the chute may be more easily cleaned when necessary.

Fig. 8 illustrates in section a modified form of chute in which the channel, although V-shaped, is formed with small flat ledges or flanges Y at its narrowest part to support the neck or narrow part of the eyelet.

The first-motion shaft U drives the main shaft D by means of the pinion V and the wheel V', and the main shaft is thrown into gear by a suitable clutch W, which is operated by a treadle X in the manner usual in eyeletting-machines.

What I claim as my invention, and desire to secure by Letters Patent, is—

1. In a machine for piercing and eyeletting cloth or the like, the combination with a piercer and an anvil, of an eyelet-chute, the end of which is arranged to retain the material in position while it is being pierced, substantially as described.

2. In a machine for piercing and eyeletting cloth and the like, the combination with a vertically-reciprocating piercer and a laterally-moving eyelet-chute, of a permanently-fixed die or anvil against which the piercer carries the perforated material and an eyelet, and between which and a shoulder on the piercer the eyelet is pushed into the cloth or other material and clenched, and a table for supporting the material between the piercer and the end of the chute, substantially as described.

3. In a machine for piercing and eyeletting, the combination with an eyelet-chute pivotally supported, of means for moving it, an arm pivotally attached to said chute, and a clamp engaging said arm, substantially as described.

4. In a machine for piercing and eyeletting, the combination with an eyelet-chute pivotally supported, of means for moving said chute, an arm pivotally attached to the chute, and a spring-controlled clamp engaging said arm, substantially as described.

5. In a machine for piercing and eyeletting, the combination with a box for the eyelets, of a brush longitudinally movable therein, a hand-lever connected with said brush, a spring for moving said hand-lever in one direction,

5 a second lever fulcrumed upon the box and having one end underlying but unattached to the end of the hand-lever, and connections from said second lever to a moving part of the machine, substantially as described.

6. In a machine for piercing and eyeleting, an eyelet-chute having a groove with inclined flat walls provided with inwardly-projecting

narrow flanges at their point of nearest approach, substantially as described.

In witness whereof I subscribe my signature in presence of two witnesses.

THOMAS WEARDEN.
